UNITED STATES PATENT OFFICE

JOSEPH W. STANLEY, OF JOHNSTOWN, PENNSYLVANIA

SWITCH STAND

Application filed October 10, 1929. Serial No. 398,688.

This invention relates to switch-stands for operating railway track switches and has for its object the provision of a novel form of operating mechanism for such stands.

Heretofore the operating lever on this class of switch-stands has been connected to the locking sleeve by means of links or other standard mechanism requiring the use of several bolts and nuts which required considerable time to assemble and were even more troublesome to remove when repairing the stand due to their becoming rusted.

The present invention provides a novel link connection between the operating lever and locking sleeve which is free of bolts or pins and, therefore, is readily assembled and dissembled.

In the drawings:

Figure 1 is an elevation of a switch-stand constructed in accordance with this invention.

Figure 2 is a fragmentary side elevation of the upper portion of the stand.

Figure 3 is a vertical sectional elevation 25 through the stand.

Figure 4 is a sectional plan taken on the line IV—IV of Figure 3.

Figure 5 is a sectional plan taken on the line V—V of Figure 3.

Referring more particularly to the drawings the letter A designates the stand as a whole which comprises a base 2, a safety sleeve 3 being mounted in said base and yieldably held against rotation by spring pressed 35 rollers 4. A switch operating shaft 5 is journaled vertically in said base and has its lower end connected to a switch throwing lever 6, while its upper end projects materially above said base and carries an indicating sign 40al 7 at its upper end.

A squared sleeve 8 is mounted around the squared upper end of the shaft 5 and has its lower end in engagement with the safety sleeve 3, while its upper end is locked to the shaft 5 by a pin or bolt 9 thus preventing

vertical movement of the shaft 5 and sleeves 3 and 8 while permitting rotary movement of the shaft 5 and sleeve 8 relative to said base.

A locking sleeve 12 is mounted around the sleeve 8 and has its lower end squared, as at 13, to fit around said sleeve 8 and prevent rotation of said sleeves relative to each other. The sleeve 12 is free to slide vertically relative to the sleeve 8.

The lower end of the sleeve 12 is reduced 55 externally to form a squared locking portion 14 and shoulder 15. The corners of the squared portion 14 are adapted to be engaged in vertical grooves 16 in the upper end of the safety sleeve 3 when the sleeve 12 is in its 60 lowermost position while the shoulder 15 engages the upper end of the sleeve 3. When the portion 14 of the sleeve 12 is engaged in the grooves 16 the sleeve 12, sleeve 8 and shaft 5 are all held against rotation. 65

An operating lever 16^a having a forked attaching end 17 is pivotally connected to the sleeve 8 at a point materially above the upper end of the sleeve 12 by a bolt or pin 18 for vertical swinging movement. The forked 70 ends 17 of said lever are provided with hollow cylindrical enlargements 19 adjacent their ends which open inwardly.

The sleeve 12 is also provided with hollow cylindrical enlargements 20 at diametrically opposite points adjacent its upper end. A pair of connecting links 21 having cylindrical projections 22 adjacent each end are mounted with their projections in said hollow recesses so as to form pivoted link connections between the lever 16^a and the sleeve 12. 75

The lever 16^a is provided with an elongated slot 24 intermediate its ends which is adapted to fit over a rigid apertured lug 25 on the sleeve 12 and to be locked against vertical swinging movement by a pad-lock 26 secured in the aperture of the lug 25. 80

In operation, when it is desired to operate the switch the pad-lock 26 will be removed 85 and the lever 16^a swung upwardly thus caus- 90

ing the links 21 to pull the sleeve 12 upwardly, releasing said sleeve 12 from the sleeve 3 and permitting the rotation of the shaft 5 to operate the switch.

The links 21 are of novel construction and are pivotally mounted by means of the integral projections 22, thus eliminating the use of bolts or pins for this purpose.

It will be understood that while this invention has been shown in connection with a "high" type switch-stand it is not limited thereto but may be applied to either the high or low type stands.

While I have shown and described a certain specific embodiment of my invention it will be understood that I do not wish to be limited thereto since various modifications may be made without departing from the scope thereof, as defined in the appended claims.

I claim:

1. In a switch-stand the combination of a base, a vertical shaft mounted centrally within said base and rotatable relative thereto, a sleeve mounted around said shaft and rotatable therewith, said sleeve being held against downward movement, and means for preventing vertical movement of said shaft relative to said sleeve, a second sleeve mounted around said first named sleeve and slideable vertically relative thereto, said second sleeve being held against rotation relative to said first named sleeve, said second named sleeve engaging said base and being held against rotation when in its lowermost position and being out of engagement with said base and free to rotate with said first named sleeve and said base when in its upper position, a forked operating lever pivotally mounted on said first named sleeve for vertical swinging movement, and a pair of link members connecting the opposite forked ends of said lever with diametrically opposite points of said second named sleeve, said forked ends of said lever being provided with hollow cylindrical enlargements adjacent their ends and opening inwardly, said second named sleeve being also provided with hollow cylindrical enlargements at diametrically opposite points adjacent its upper end, and said links being provided with cylindrical projections adjacent each end which fit loosely within said hollow enlargements forming pivotal connections.

2. In a switch-stand structure a vertically fixed and rotatable member, a sleeve slidably mounted for vertical movement on said member and held against rotary movement relative thereto, a forked operating lever pivotally mounted on said member at a point materially above the upper end of said sleeve for vertical swinging movement, and a pair of link members connecting the opposite forked ends of said lever with diametrically opposite points of said sleeve, said forked ends of said lever being provided with hollow cylindrical

enlargements adjacent their ends and opening inwardly, said sleeve being also provided with hollow cylindrical enlargements at diametrically opposite points adjacent its upper end, and said links being provided with cylindrical projections adjacent each end which fit loosely within said hollow enlargements forming pivotal connections.

In testimony whereof, I have hereunto set my hand.

JOSEPH W. STANLEY.
